UNITED STATES PATENT OFFICE.

THOMAS DOUGLAS JONES AND JOHN H. BARR, OF KANSAS CITY, MISSOURI; MARY BARR EXECUTRIX OF SAID JOHN H. BARR, DECEASED.

STOP MECHANISM FOR PHONOGRAHPS.

Application filed September 6, 1921. Serial No. 498,826.

To all whom it may concern:

Be it known that we, THOMAS D. JONES and JOHN H. BARR, citizens of the United States, and residents of Kansas City, Jackson County, State of Missouri, have invented a certain new and useful Improvement in Stop Mechanism for Phonographs, of which the following is a complete specification.

The present invention relates to stop mechanism for phonographs, and aims to provide an improved stop device for automatically effecting the release of the brake for stopping the motion of the record, regardless of the length of the record groove or of the character of the groove at the end of the record.

Accordingly, we have devised a novel form of stop mechanism, in which we provide the brake with a releasing connection having means for automatically tripping the same at the end of the record, which tripping means include a pair of relatively movable elements, one of which is actuated by the movement of the tone or reproducer arm of the phonograph, while the other of said elements is adapted for movement in response to the rotary movement of the record, and means also being provided for causing said tripping means to be actuated by the separating action of said elements due to the continuing movement of one of them after the stopping of the tone arm at the end of the record.

It is further sought to provide a stop mechanism of the character described in which the relatively movable elements which are responsive, respectively, to the movement of the tone arm and the rotation of the record, are provided with a tripping device which is carried by one of the elements and adapted to be latched by engaging with the other element, so that on the separation of the elements due to the tone arm having reached the end of the playing groove on the record, the tripping device will automatically be released for tripping the releasing connection to the brake.

It is a further object to provide a practical and efficient, and yet comparatively simple construction for carrying out the desired objects of the invention, and which will require no other attention for its proper operation than the setting of the brake and

the returning of the tone arm to original position after the playing of the record.

With the foregoing general objects in view, as well as minor objects which will appear in the course of the detailed description, the invention will now be described by reference to the accompanying drawings illustrating one form of construction which we have devised for embodying the proposed improvements, after which the novel features therein will be particularly set forth and claimed.

In the drawings—

Figure 1 is a plan view of a phonograph equipped with a stop mechanism constructed in accordance with the present invention, with parts of the tone arm, record and turn-table broken away to disclose the mechanism beneath;

Figure 2 is a view similar to that shown in Figure 1, but largely broken away to illustrate only the parts of the stop mechanism proper, and with the brake in released position;

Figures 3, 4, 5, 6 and 7 are enlarged detail sectional views taken on the lines III—III, IV—IV, V—V, VI—VI and VII—VII, respectively, of Figure 1;

Figures 8 and 9 are detail views illustrating the clutch device provided for intermittently clutching and moving one of the slide elements forming a part of the means for tripping the brake releasing connection, Figure 9 illustrating said clutch device held out of clutching engagement with the pull member which is connected with one of the slide elements.

Referring now to the said drawings in detail, these illustrate the improved stop construction as applied to an ordinary form of phonograph comprising the usual cabinet 10, turn-table 11, supported on the upper end of a vertical shaft 12, driven from the usual motor (not shown) inside the cabinet 10, and a tone or reproducer arm 14 mounted upon the usual supporting connections 15 with the tone chamber within the cabinet 10, the said arm 14 being provided with the usual reproducer 16 fitted with a needle 17 adapted to travel in the playing groove 18 of a record 19 supported upon the turn-table 11. The tone or reproducer arm 14 is mounted for movement

across the record 19 from the beginning of the groove 18 at the outer margin of the record to the end of said groove in the vicinity of the center of the record, as is usual in the case of records of the disc form.

In illustrating the improved stop mechanism, we have shown the same in relation to a brake lever 20 pivoted at 21 beneath the turn-table 11 and provided with a shoe portion 22 for gripping engagement with the outer margin of the table 11, a spring 23 connected with a link 24 attached to said lever being also provided for actuating the same into operative or braking position whenever released by the mechanism hereinafter described.

The other end of the link 24 is pivotally connected with a lever 25 operating about a fixed pivot 26 and adapted to be engaged by a latch member 27 which is actuated by a spring 28 and, when engaged with the free end of the lever 25, serves to hold the latter with the brake in released position, as shown in Figure 1; or, when disengaged from said lever 25, allows the brake to respond to the action of its spring 23 and be thereby moved into operative position, at which time the lever 25 and latch 27 will occupy the relative positions shown in Figure 2.

The latch 27 is designed to be released from engagement with the lever 25 by the action of a latch engaging member 29 which is pivotally mounted alongside a track 30, the ends of the member 29 being carried by pivot bearings 31 at the opposite ends of the track 30, so that the latch engaging member 29 extends the full length of the track 30, with one end of said member maintained in engagement with one end of the latch 27, as clearly illustrated in Figures 1, 2 and 5.

Mounted for sliding movement along the track 30 is a pair of slide elements 32 and 33, adapted for a slight degree of relative movement, and the element 32 slidably engaging an extension 34 from the element 33, and said extension being formed with a stop lug 35 whereby the extent of relative movement between the elements 32 and 33 is limited. The slide element 32 is provided with an arm 36 which is pivotally connected with an arm 37 projecting downward from the tone or reproducer arm 14, so that as the arm 14 is caused to move inwardly across a record in the playing thereof, a corresponding movement is imparted to the slide element 32 in the direction of the inner end of the track 30, as will be readily understood. A similar sliding movement would naturally be imparted to the slide element 33 by this action of the tone arm and the movement transmitted thereby to the slide element 32; but in order to insure a positive feeding movement to said slide element 33, independent of any feeding

action of the tone arm, we provide means, operated from the vertical shaft 12, for effecting a sliding movement of the element 33 at substantially the same rate of movement as that imparted to the element 32. This means comprises an arm 40 swinging about a fixed pivot 41 and provided with a yoke portion 42 embracing a cam or eccentric 43 fixed to the central portion of a gear wheel 44 journaled upon a shaft stub 45 and meshing with a pinion 46 secured to the shaft 12. The throw of the arm 40 by the eccentric 43 is regulated by an adjusting screw 47 carried by one arm of the yoke 42. The arm 40 also carries a clutch lever 48 pivotally connected to said arm as indicated at 49, and formed at one end of said lever with a suitable eye or opening 50 for the passage of a pull link 51, one end of which link is pivotally connected, as indicated at 52, with the slide element 33.

Associated with the clutch lever 48 is a suitable spring 53, the action of which spring 53 is to maintain that end of the lever having the opening or eye 50 in clutched relation to the link 51, it being understood that, by this arrangement of clutch means, the link 51 may be thrust forward freely through the opening 50 (that is, in the direction of the right in Figures 1, 2, 8 and 9), but reverse movement of the link 51 will be prevented so long as the lever 48 is subjected to the action of the spring 53, as illustrated in Figure 8. This means, therefore, that any movement of the lever 40 to the right in Figures 1 and 2 will result in a feeding movement of the element 33 to the right, if the lever 48 is acted upon by the spring 53 in the manner shown in Figures 1 and 8. Since it is desired, however, to have the lever 48 relieved of the action of the spring 53 after the brake has been applied, this result is obtained by providing the lever 25 with an arm or extension 55 adapted to engage one end of the lever 48 and rock it against the action of the spring 53, as illustrated in Figure 9, whereupon the clutch lever 48 will not interfere with the reverse movement of the link 51, as is required in the return of the tone arm 14 to its original position opposite the outer margin of the turn-table.

The forward slide element 33 carries a pivoted tripping device in the form of a lever 60 having a pivot pin 61 (see Figure 6) journaled transversely of the slide element 33 and provided with a coil spring 62 for automatically actuating the lever 60 into tripping engagement with the latch engaging member 29, the position of this latter member 29 alongside the track 30 and the full length thereof affording opportunity for the tripping action of the lever 60 in any position of said lever, which position varies, of course, with the length of

the record. The rear end of the lever 60 is adapted to be engaged by a latch lug 65 (see Figure 7) formed on the other slide element 32 and adapted to maintain the 5 tripping lever 60 latched in retracted or inoperative position so long as the slide elements 32 and 33 are engaged or in contact with each other, as when they are moving substantially in unison along the track 30 10 during the playing of a record. However, when said slide elements 32 and 33 become separated, as occurs on stopping of the tone arm and of the slide element 32, and as a result of a continued movement of the 15 sliding element 33 in response to the continued rotation of the shaft 12 and of the record 19, the tripping lever 60 will become released from latching engagement with the lug 65 and actuated by its spring 62 into 20 tripping engagement with the member 29 and thereby effecting operation of the latch 27 to release the lever 25 and applying the 25 brake 22.

It is, of course, necessary to reset the 25 tripping device at the end of each tripping operation, and this is accomplished automatically by the return or reverse movement of the tone arm 14 into its original position, in which movement the laterally 30 projecting finger 67 at the forward end of the tripping lever 60 is carried across a cam edge 68 formed on a bracket 69 mounted in the path of said finger 67. The engagement of the finger 67 with the cam 35 edge 68 automatically rocks the tripping lever 60 into inoperative position so as to permit ready re-engagement of the lug 65 with the other end of said lever 60 as the tone arm 14 is moved slightly forward again 40 in the setting of the needle 17 in the first spiral of the groove 18.

In explanation of the operation of the improved construction, it will be understood that the turn-table is stationary with 45 the brake 22 applied whenever a record is placed upon the turn-table preparatory to playing the same, and in this position of the parts the arm 55 of the lever 25 maintains the clutch lever 48 inoperative (see 50 Figure 2), thereby permitting any necessary movement of the tone arm and slide elements 32 and 33 for the purpose of setting the needle 17 at the beginning of the record groove. With the slide elements 32 55 and 33 in engagement with each other, for the purpose of latching the tripping device or lever 60 in inoperative position, the brake lever 20 will be swung outwardly against the action of its spring 23 for removing 60 the brake shoe from engagement with the table 11, which will result in automatically latching the lever 25 with the latch member 27, the springs 28 and 62 yielding sufficiently to permit this latching engagement 65 to be effected. Now as the playing of the

record proceeds, the slide elements 32 and 33 will move together substantially in unison across the record, the element 32 moving primarily in response to the movement imparted thereto from the tone arm, while the slide element 33 is propelled along partly by the movement imparted thereto from the slide element 32 and partly in response, during the movement of the tone arm, to the feeding action imparted thereto by the pull link 51, as already explained. When the movement of the tone arm 14, however, ceases, the slide element 32 also stops and the slide element 33 responds solely to the feeding movement imparted thereto from the rotary action of the shaft 12. This feeding action through the medium of the clutch lever 48 has, during the movement of the tone arm, tended to effect a sliding movement of the element 33 at the same rate as the slide element 32, and now continues this feeding movement after the stopping of the slide element 32, with the result that the elements 32 and 33 become slightly separated, thereby automatically releasing the 90 tripping lever 60 into tripping engagement with the member 29, which in turn operates the latch 27 out of engagement with the lever 25, and thus releasing said lever 25 to permit the application of the brake. 95 This release of the lever 25 again results in engagement of the arm 55 with the clutch lever 48, and holds the latter inoperative until the brake lever 20 is again moved into the position shown in Figure 1, that is, 100 after the parts have been set ready for the playing of a new record. The reverse movement of the tone arm 14 and resetting thereof have, as already explained, resulted in the resetting of the tripping device, on 105 account of the action of the cam edge 68.

From the foregoing it will be apparent that we have provided a practical and most efficient arrangement and construction for fulfilling the requisite function of a stop 110 mechanism of the character described, and one which will operate regardless of the length of the record or playing groove, or of the nature of such groove at the end of the record, this end portion of the groove 115 in some cases assuming an outline designed to mechanically actuate the tone arm for the purpose of tripping a stop mechanism; the improved mechanism which we have described performs the required function 120 for all types and forms of grooves, and requires no attention on the part of the player other than seeing to it that the tone arm is moved sufficiently in the reverse direction to insure the resetting and relatching 125 of the trip device.

While we have shown and described what we now regard as the preferred form of construction for embodying the improvements, we desire to reserve the right to 130

make such changes or modifications as may fairly fall within the scope of the appended claims.

What we claim is:

5. 1. An automatic stop for phonographs comprising, in combination with the tone arm and rotating record, a brake provided with a releasing connection, and means for tripping said releasing connection including a pair of elements moving substantially in unison during the travel of said tone arm, one of said elements being adapted to continue its movement, on stopping of said tone arm, in response to the continued rotation of the record, and a tripping device carried by one of said elements and adapted to be locked by engagement with the other element, whereby on separation of said elements said device is released for tripping said releasing connection. 75
10. 2. An automatic stop for phonographs comprising, in combination with the tone arm and rotating record, a brake provided with a spring latch for releasing said brake, and means for tripping said latch including a track, a pair of elements mounted for travel substantially in unison along said track and provided with a tripping device adapted to be actuated by separation of said elements, a latch engaging member pivoted alongside said track for engagement by said tripping device in any position of the latter, and means operated by the continued movement of the record after stopping of said tone arm for separating said elements. 80
15. 3. An automatic stop for phonographs comprising, in combination with the tone arm and rotating record, a brake provided with a spring latch for releasing said brake, and means for tripping said latch including a track, a pair of elements mounted for travel substantially in unison along said track and provided with a tripping device adapted to be actuated by separation of said elements, one of said elements being moved in response to the travel of said tone arm and the other element having a final additional movement imparted thereto by the continued rotation of the record after stopping of said tone arm, thereby separating said elements, and a latch engaging member pivoted alongside said track for engagement by said tripping device in any position of the latter. 85
20. 4. An automatic stop for phonographs comprising, in combination with the tone arm and rotating record, a brake provided with a spring latch for releasing said brake, and means for tripping said latch including a track, a pair of elements mounted for travel substantially in unison along said track and provided with a tripping device adapted to be actuated by separation of said elements, one of said elements being moved in response to the travel of said tone arm and the other element having a final additional movement imparted thereto by the continued rotation of the record after stopping of said tone arm, thereby separating said elements, a latch engaging member pivoted alongside said track for engagement by said tripping device in any position of the latter, and means acting automatically to relatch said tripping device as said tone arm is returned to its original position. 90
25. 5. An automatic stop for phonographs comprising, in combination with the tone arm and rotating record, a brake provided with a spring latch for releasing said brake, and means for tripping said latch including a track, a pair of elements mounted for travel substantially in unison along said track and provided with a tripping device adapted to be actuated by separation of said elements, one of said elements being moved in response to the travel of said tone arm and the outer element having a final additional movement imparted thereto by the continued rotation of the record after stopping of said tone arm, thereby separating said elements, a latch engaging member pivoted alongside said track for engagement by said tripping device in any position of the latter, a connection between said elements whereby both are retracted by the return of the tone arm to original position and means acting automatically to relatch said tripping device as said tone arm is returned to original position. 95
30. 6. An automatic stop for phonographs comprising, in combination with the tone arm and rotating record, a brake provided with a releasing connection, and means for tripping said releasing connection including a pair of relatively movable elements, one of said elements being actuated by the movement of said tone arm, a member attached to the other of said elements and provided with a clutch device actuated by the rotation of said record to move said other element at substantially the same rate as said first element during the movement of the tone arm, and a tripping device set in operation by separation of said elements, on stopping of said tone arm, to trip said releasing connection. 100
35. 7. An automatic stop for phonographs comprising, in combination with the tone arm and rotating record, a brake provided with a releasing connection, and means for tripping said releasing connection including a pair of relatively movable elements, one of said elements being actuated by the movement of said tone arm, a member attached to the other of said elements and provided with a clutch device reciprocated by the rotation of the record to intermittently move said other element at substantially the same rate as said first element during the movement of the tone arm, and a tripping connection. 105
40. 8. An automatic stop for phonographs comprising, in combination with the tone arm and rotating record, a brake provided with a releasing connection, and means for tripping said releasing connection including a pair of relatively movable elements, one of said elements being actuated by the movement of said tone arm, a member attached to the other of said elements and provided with a clutch device reciprocated by the rotation of the record to intermittently move said other element at substantially the same rate as said first element during the movement of the tone arm, and a tripping connection. 110
45. 9. An automatic stop for phonographs comprising, in combination with the tone arm and rotating record, a brake provided with a releasing connection, and means for tripping said releasing connection including a pair of relatively movable elements, one of said elements being actuated by the movement of said tone arm, a member attached to the other of said elements and provided with a clutch device reciprocated by the rotation of the record to intermittently move said other element at substantially the same rate as said first element during the movement of the tone arm, and a tripping connection. 115
50. 10. An automatic stop for phonographs comprising, in combination with the tone arm and rotating record, a brake provided with a releasing connection, and means for tripping said releasing connection including a pair of relatively movable elements, one of said elements being actuated by the movement of said tone arm, a member attached to the other of said elements and provided with a clutch device reciprocated by the rotation of the record to intermittently move said other element at substantially the same rate as said first element during the movement of the tone arm, and a tripping connection. 120
55. 11. An automatic stop for phonographs comprising, in combination with the tone arm and rotating record, a brake provided with a releasing connection, and means for tripping said releasing connection including a pair of relatively movable elements, one of said elements being actuated by the movement of said tone arm, a member attached to the other of said elements and provided with a clutch device reciprocated by the rotation of the record to intermittently move said other element at substantially the same rate as said first element during the movement of the tone arm, and a tripping connection. 125
60. 12. An automatic stop for phonographs comprising, in combination with the tone arm and rotating record, a brake provided with a releasing connection, and means for tripping said releasing connection including a pair of relatively movable elements, one of said elements being actuated by the movement of said tone arm, a member attached to the other of said elements and provided with a clutch device reciprocated by the rotation of the record to intermittently move said other element at substantially the same rate as said first element during the movement of the tone arm, and a tripping connection. 130

device set in operation by separation of said elements, on stopping of said tone arm, to trip said releasing connection.

8. An automatic stop for phonographs comprising, in combination with the tone arm and rotating record, a brake provided with a releasing connection, and means for tripping said releasing connection including a pair of relatively movable elements, one of said elements being actuated by the movement of said tone arm, a pull member attached to the other of said elements, a pivoted arm reciprocated by the rotation of said record and carrying a clutch lever engaging said pull member and operative to intermittently move the same and said other element at substantially the same rate as said first element during the movement of the tone arm, and a tripping device set in operation by separation of said elements, on stopping of said tone arm, to trip said releasing connection.

9. An automatic stop for phonographs comprising, in combination with the tone arm and rotating record, a brake provided with a releasing connection, and means for tripping said releasing connection including a pair of relatively movable elements, one of said elements being actuated by the movement of said tone arm, a pull member attached to the other of said elements, a pivoted arm reciprocated by the rotation of said record and carrying a spring-clutch lever engaging said pull member and operative to intermittently move the same and the other of said elements at substantially the same rate as said first element during the movement of the tone arm, a tripping device set in operation by separation of said elements, on stopping of said tone arm, to trip said releasing connection, and means acting to maintain said clutch lever inoperative while said brake is in released position.

10. An automatic stop for phonographs comprising in combination with the tone arm and rotating shaft, a brake provided with a releasing connection, and means for tripping said releasing connection including a pair of elements, means actuated by said shaft for imparting movement to one of said elements, means for producing travel of the other of said elements in response to the movement of the tone arm and simultaneously actuating the first element at the same rate of speed independently of its actuation by said shaft, said shaft-actuated means operating after the stopping of the tone arm to impart a final additional movement to said first element and a tripping device set in operation by such continued operation of said first element.

11. An automatic stop for phonographs comprising in combination with the tone arm and rotating shaft, a brake provided

with a releasing connection, and means for tripping said releasing connection including a pair of elements adapted for simultaneous movement, one of said elements being operated by the tone arm and effecting movement of said other element, means actuated by the rotating shaft for imparting a final additional movement to said second element after the stopping of said tone arm, and a tripping device set in operation by the continued movement of said second element.

12. An automatic stop for phonographs comprising in combination with the tone arm and rotating shaft, a brake provided with a releasing connection, and means for tripping said releasing connection including a pair of elements, one of said elements being actuated in response to the rotation of the shaft and the other element being actuated in response to the movement of the tone arm; said tone arm-actuated element being susceptible of operation at a faster rate of speed than said shaft-actuated element, and means whereby upon the stopping of said tone arm-actuated element, the shaft-operated element through its continued movement shall effect actuation of said brake.

13. An automatic stop for phonographs, comprising in combination with the tone-arm and rotating-shaft, a brake, a pair of elements driven by said tone-arm and rotating-shaft respectively, said tone-arm element being adapted to effect movement of said rotating-shaft element, a connection between said rotating-shaft element and rotating-shaft permitting the former to be moved by the tone-arm element regardless of the rate of speed of the rotating-shaft, said connection being adapted to impart additional movement to said shaft element upon the stoppage of the tone-arm, and a connection for actuating the brake in response to the additional movement of said shaft element.

14. An automatic stop for phonographs comprising in combination with the tone arm and rotating shaft, a brake, a pair of elements adapted for simultaneous movement, one of said elements being actuated by the tone arm and adapted to effect movement of said other element, a clutch operated in response to said rotating shaft, a link connecting said clutch and said second-named element and adapted to impart movement to the latter when the movement of the tone arm has ceased, and a connection for actuating the brake in response to the additional movement of said second element.

In witness whereof we hereunto affix our signatures.

TOM DOUGLAS JONES,
JOHN H. BARR,
